UNITED STATES PATENT OFFICE.

GRAY I. MORRISS, OF CHICAGO, ILLINOIS, ASSIGNOR TO RELIANCE DRYING ROOM COMPANY, OF CHICAGO, ILLINOIS, A CORPORATION OF ILLINOIS.

DRYING-ROOM.

1,181,334.

Specification of Letters Patent. Patented May 2, 1916.

Application filed May 29, 1915. Serial No. 31,195.

To all whom it may concern:

Be it known that I, GRAY I. MORRISS, a citizen of the United States, residing at Chicago, in the county of Cook and State 5 of Illinois, have invented certain new and useful Improvements in Drying-Rooms, of which the following is a specification.

The present invention relates to a drying room arranged and adapted for use in drying fillers, stains, varnishes, enamels, and kindred liquid and pigment products.

The object of the invention is to provide means for establishing a circulation of air through the drying room, and for educting 15 a certain portion of said circulated air during the circulating process without the use of supplemental draft producing appliances for causing the eduction current.

The invention further consists in the features of construction and combinations of parts hereinafter described and claimed.

In the drawings: Figure 1 is a perspective of a drying room equipped according to the teachings of the present invention; Fig. 2 25 is a section showing the eduction means; and Fig. 3 is a view looking toward one side wall of said room.

The room is formed of an upper wall or ceiling 4, a side wall 5 and floor 6. The 30 walls 4 and 5 are, as shown, each of hollow construction providing air chambers 7 and 8 respectively. The side walls, as will be seen from Fig. 3, are divided into a series of compartments or flues by means of up- 35 rights 9, the same being the usual and ordinary studdings of a building.

Located within the interior of the room and extending parallel with, but spaced away from, the side wall 5 are screens 10, 40 each of which terminates short of the ceiling and floor of the room, leaving an upper opening 11 and a lower opening 12. In the space intermediate the screens and side wall with which they are associated, are heating 45 members 13 which may be of any suitable nature, and, as shown, consists of the ordinary steam coils supported by a suitable brace 14. A suitable air inlet duct 15 may be provided for admitting fresh air into the 50 interior of the room.

Suspended from the ceiling and located approximately midway between the side walls are cooling coils 16. The fresh air enters the spaces between the screens 10 and 55 side walls with which they are associated,

passes over the coils 13, becomes heated and rises in the spaces between the screens and their associated side walls, passes into the room through the openings 11, and encounters the cooling coil 16 by means of 60 which it is cooled; and by such cooling action caused to descend into the interior of the room and about the article or substance which is being treated. The air then passes through the opening 12, is reheated by the 65 coils 13 and rises as before described. In order to more efficiently direct the flow of air, baffles 17 are provided at the upper portion of the room.

The foregoing describes the arrangement 70 for heating and cooling the air and causing the circulation thereof. The main principle involved in this, however, is old in the art, and no claim is made broadly thereto in the present invention. The gist of the present 75 invention lies in the means for educting a portion of the circulated air which serves to increase the circulation of the air and allows of a steady changing of the air to prevent its becoming too heavily laden with 80 fumes, and to carry out this eduction without the use of supplemental draft producing devices, using the heating means for causing the eduction flow. This eduction means in the construction shown, comprises a triangular shaped hood 18, which extends across the space between each of the screens 10 and the side walls with which such screens are 85 associated. The hood, as shown, is formed with a closed top wall 19 and closed side 90 walls 20, but is open at its bottom 21. The hood communicates with the opening 22 in the inner side wall 23, and this in turn communicates with one of the spaces or flues 24 formed by the studdings 9 between the 95 inner side wall 23 and the outer side wall 25. A port or opening 26 is provided at the top of the flue 24, out of which the educted air passes, as will be seen from Fig. 3. The hood 18 is of a size so that it extends between two adjacent of the studdings 9, and these hoods are interposed or positioned at periodical intervals in the spaces between the screens 10 and their associated side walls, thus providing a certain and relative 100 amount of eduction opening, so that a certain percentage of the air which is being circulated is taken out from the room. This, as stated, serves to constantly change the air 105 so as to prevent it from becoming too heavily 110.

laden with fumes. The eduction openings are located above the heating means, so that the acceleration of the air caused by its passing over the heating means gives to the 5 air sufficient momentum to cause it to travel through the eduction passage, and hence no auxiliary draft producing means are necessary to cause the eduction flow.

Although the invention has been described 10 with considerable particularity, it is understood that changes may be made in the structure described without departing from the spirit of the invention, provided the structure produced is maintained within the con- 15 fines of the appended claims.

I claim:

1. In a drying room, in combination with inclosing walls, a ventilating flue located behind one of the inclosing walls, a screen 20 located in front of said wall and open at the top and bottom for communication with the interior of the drying room, heating means located behind the screen, means adapted to establish communication between the space 25 intermediate the wall and screen and said ventilating flue to educt a portion of the circulated air, said means opening to said space above the heating means, and means for admitting fresh air, substantially as de- 30 scribed.

2. In a drying room, in combination with inclosing walls, a ventilating flue located behind one of the inclosing walls, a screen located in front of said wall and open at the 35 top and bottom for communication with the interior of the drying room, heating means located behind the screen, a deflecting member above the heating means extending across the space intermediate the inclosing wall 40 and screen and in communication with the ventilating flue for diverting a portion of the circulated air into said ventilating flue, and means for admitting fresh air, substantially as described.

45 3. In a drying room, in combination with inclosing walls, a screen located in front of one of said walls and open at the top and bottom for communication with the interior

of the drying room, heating means located between the screen and wall, means located 50 above the heating means for educting a portion of the air rising from said heating means, and means for admitting fresh air, substantially as described.

4. In a drying room, in combination with 55 inclosing walls, a screen located in front of one of said walls and open at the top and bottom for communication with the interior of the drying room, a series of eduction passages in the space between said wall and 60 screen, and located above said heating means, said passages being located at periodical points to extract a portion of the heated air rising from said heating means, and means for admitting fresh air, substan- 65 tially as described.

5. In a drying room, in combination with inclosing walls, a screen located in front of one of said walls and open at the top and bottom for communication with the interior 70 of the drying room, heating means located between said screen and wall, an eduction passage communicating with the space between the screen and wall and located above the heating means, and a deflector for diverting a portion of the air rising from 75 said heating means into said eduction passage, substantially as described.

6. In a drying room, in combination with inclosing walls, a ventilating flue located 80 behind one of the inclosing walls, a screen located in front of said wall and open at the top and bottom for communication with the interior of the drying room, heating means located behind the screen and below 85 the intake for the ventilating flue, and a hood adjacent to the intake and projecting into the space intermediate the wall and the screen at a point above the heating means for diverting a portion of the heated air 90 into the ventilating flue, substantially as described.

GRAY I. MORRISS.
